Primary Examiner — John Windmuller(74) *Attorney, Agent, or Firm* — Muncy, Geissler, Olds & Lowe, PC(57) **CLAIM**

The ornamental design for an antenna, as shown and described.

DESCRIPTION

FIG. 1 is a front elevational view of an antenna showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view thereof;

FIG. 8 is a rear perspective view thereof;

FIG. 9 is a perspective view thereof, showing the antenna in use; and,

FIG. 10 is another perspective view thereof, showing the antenna in use.

The light grey areas surrounded by broken lines are portions of the antenna that form no part of the claimed design.

1 Claim, 10 Drawing Sheets(56)
